[57] CLAIM

The ornamental design for a portfolio, as shown and described.

DESCRIPTION

FIG. 1 is an elevational view of a portfolio showing my new design in open condition;

FIG. 2 is a perspective view thereof in a partially closed condition with the top flaps lifted;

FIG. 3 is a perspective view thereof in a partially closed condition with the top flaps lowered;

FIG. 4 is a perspective view thereof in a partially closed condition as seen from the rear side;

FIG. 5 is an elevational view showing a modified form of FIG. 1 in open condition, and wherein the only difference resides in the absence of a pair of score lines in the upper flap members; and,

FIG. 6 is a perspective view of the alternative embodiment in a partially closed condition with the top flaps lowered.
